UNITED STATES PATENT OFFICE.

ALPHONSO KESSLER, OF DUNKIRK, NEW YORK.

SCARFPIN-HOLDER.

1,348,120.

Specification of Letters Patent. Patented July 27, 1920.

Application filed June 7, 1918. Serial No. 238,716.

To all whom it may concern:

Be it known that I, ALPHONSO KESSLER, a citizen of the United States, residing at Dunkirk, in the county of Chautauqua and State of New York, have invented new and useful Improvements in Scarfpin-Holders, of which the following is a specification.

This invention is an improved device for application to a scarf or hat pin to prevent the pin from being casually withdrawn or detached, the object of the invention being to provide a pin holding device of this character which is extremely cheap and simple and which can be readily applied to and removed from a hat or scarf pin.

In the accompanying drawings:—

Figure 1 is a perspective view of a scarf pin holder constructed and arranged in accordance with my invention and showing the same attached to a scarf pin.

Fig. 2 is a detail perspective view of the holder.

Fig. 3 is a similar view showing a modified form of the holder.

Fig. 4 is a view of the holder partly in section, showing the same associated with a fragmentary portion of a pin.

My scarf pin holder comprises a strip 1 of sheet spring steel or other suitable material and which is formed at one end with an opening 2 through which a scarf pin may be passed, the said end curved as at 3 and arranged at an angle to the body of the strip 1. At the opposite end the said strip 35 is bent to form a hook 4 which is arranged

at right angles to the body of the strip and which extends therefrom on the same side as the end 3 the bill 5 of the hook extending transversely and being adapted to be engaged with the pin so that the strip 40 1 is put under tension and the holder is caused to effectually and tightly grip the pin at the opening 2 and also by the hook. The holder cannot become casually detached from the pin and hence the pin cannot be 45 come casually detached from the scarf in which it is used.

In the form of my invention shown in Fig. 3 the holder is formed with a pair of oppositely extending bills 6 at the hook end 50 7 and either of which may be engaged with the pin.

Having thus described my invention, I claim:—

A scarf pin holder comprising a flat piece 55 of spring metal, including a body portion arranged parallel to the pin, one end of the body portion being disposed at an inclination to the pin and having an opening for the reception of the latter said opening having its axis obliquely disposed with respect to the pin, the opposite end of the body portion being disposed at a right angle and terminating to provide a duplex hook, the hook portions being arranged opposite the 60 adjacent longitudinal edges of the body portion for the purpose specified.

In testimony whereof I affix my signature.

ALPHONSO KESSLER.
